[57] CLAIM

The ornamental design for scissor handles, as shown and described.

DESCRIPTION

FIG. 1 is a perspective view of the scissor handles showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a bottom plan view thereof;

FIG. 7 is a perspective view of a second embodiment of our new design;

FIG. 8 is a front elevational view thereof; and,

FIG. 9 is a left side elevational view thereof.

The broken line illustration of the blades is for illustrative purposes only and forms no part of the claimed design.
